DESIGN FOR A BENCH

Leo G. Haase, Hollywood, Calif.

Application February 2, 1940, Serial No. 89,953

Term of patent 14 years

To all whom it may concern:

Be it known that I, Leo G. Haase, a citizen of the United States and residing in Hollywood, in the county of Los Angeles and State of California, have invented a new, original, and ornamental Design for a Bench, of which the following is a specification, reference being had to the accompanying drawing, forming a part thereof.

In the accompanying drawing, Fig. 1 is a perspective view of a bench showing my design; and Fig. 2 is an end elevational view of the bench.

I claim:

The ornamental design for a bench, substantially as shown.

LEO G. HAASE.
